US0D1021967S

(12) **United States Design Patent** (10) Patent No.: **US D1,021,967 S**
(45) Date of Patent: ** Apr. 9, 2024

(54) **WORK VEHICLE, TOY, REPLICA AND/OR DISPLAY SCREEN WITH VIRTUAL MODEL THEREOF**

(71) Applicant: **Deere & Company**, Moline, IL (US)

(72) Inventors: **Randy C. Rush**, Cedar Falls, IA (US); **Arlyn Wilcox**, Grundy Center, IA (US); **Piyush Choudhary**, Pune (IN); **Ryan G. Brown**, Waterloo, IA (US); **Benjamin D. Dunnigan**, Cedar Falls, IA (US)

(73) Assignee: **DEERE & COMPANY**, Moline, IL (US)

(**) Term: **15 Years**

(21) Appl. No.: **29/725,287**

(22) Filed: **Feb. 24, 2020**

(51) LOC (14) Cl. **15-03**

(52) U.S. Cl.

USPC **D15/26**
